CLAIM

The ornamental design for a floor tile, as shown and described.

DESCRIPTION

FIG. 1 is a front, left and bottom perspective view of a first embodiment of a floor tile, showing my new design; FIG. 2 is a rear, right and top perspective view thereof; FIG. 3 is a front elevational view thereof; FIG. 4 is rear elevational view thereof; FIG. 5 is a left side elevational view thereof; FIG. 6 is a right-side elevational view thereof; FIG. 7 is a top plan view thereof; FIG. 8 is a bottom plan view thereof; FIG. 9 is an enlarged detail view of portion 9 encircled in FIG. 1; FIG. 10 is an enlarged detail view of portion 10 encircled in FIG. 2; FIG. 11 is a front, left and bottom perspective view of a second embodiment of a floor tile; FIG. 12 is a rear, right and top perspective view thereof; FIG. 13 is a front elevational view thereof; FIG. 14 is rear elevational view thereof; FIG. 15 is a left side elevational view thereof; FIG. 16 is a right-side elevational view thereof; FIG. 17 is a top plan view thereof; FIG. 18 is a bottom plan view thereof; FIG. 19 is an enlarged detail view of portion 19 encircled in FIG. 11; and, FIG. 20 is an enlarged detail view of portion 20 encircled in FIG. 12.

The dot-dash broken lines depict the boundaries of the enlargements that form no part of the claimed design.

1 Claim, 20 Drawing Sheets
